UNITED STATES PATENT OFFICE

2,598,119

CHUCK WRENCH EJECTOR

John W. Goff, St. Paul, Minn.

Application May 9, 1949, Serial No. 92,098

3 Claims. (Cl. 81—71)

1

My present invention relates generally to wrenches or keys for manually-operated chucks and the like and, more specifically, to ejector attachments for such chuck wrenches.

In the operation of a lathe, drill press or the like, the operator will occasionally forget to remove the wrench or key from the work-holding chuck after the tightening thereof about a work piece. Rotation of the chuck causes the wrench to be forcibly ejected under centrifugal action; and danger to the operator or other persons nearby, or damage to the machine, often results. The primary object of my invention, therefore, is the provision of an attachment for chuck wrenches which will automatically remove such a wrench from a chuck upon release of manual pressure thereon.

Another highly important object of my invention is the provision of an attachment as set forth, which will protect the chuck-engaging head of the wrench when said wrench is not in use.

Still another object of my invention is the provision of an attachment as set forth, which may be quickly and easily secured to a chuck wrench or key.

A still further object of my invention is the provision of a device as set forth, which is inexpensive to manufacture, simple and rugged in construction, and efficient and durable in use.

Other highly important objects and advantages of my invention will become apparent from the following detailed specification, appended claims, and attached drawings.

Referring to the drawings, in which like characters indicate like parts throughout the several views:

Fig. 1 is a view in side elevation of my novel attachment secured to a chuck wrench and applied to a lathe chuck;

Fig. 2 is an enlarged fragmentary view, partly in plan and partly in side elevation, taken substantially on the line 2—2 of Fig. 1;

Fig. 3 is a still further enlarged view in front elevation of a chuck wrench having my novel attachment thereto and shown as being removed from a chuck, some parts being broken away and some parts being shown in section;

Fig. 4 is a view in horizontal section, taken on the line 4—4 of Fig. 3; and

Fig. 5 is a horizontal section, taken on the line 5—5 of Fig. 2.

Referring with greater detail to the drawings, a multiple jaw chuck is indicated in its entirety by the numeral 1 and includes the con-

2

ventional chuck body 2 and radially-movable jaws 3. The usual jaw-actuating element or screw 4 is provided with a socket 5 which is usually rectangular in cross-section to receive the head of a chuck wrench or key 6. The chuck wrench 6 comprises a shank 7 which terminates at its lower end in a head 8 which is of the same cross-sectional shape as the socket 5, in this case, rectangular. At its upper end, shank 7 is diametrically enlarged to provide a head 9 through which extends a transverse handle 10. The chuck wrench 6 above-described is a type commonly used in connection with chucks in lathes, drill presses, and the like.

My novel attachment includes a tubular housing 11 having rigidly secured to its upper end, by screws or the like 12, a bushing 13. The bushing 13 is of a size to slide axially over the shank 7 of the wrench 6 and may be locked in place by a set screw 14 having screw-threaded engagement therewith. It will be seen, by reference to Figs. 2 and 3, that the lower end of bushing 13 provides an annular shoulder 15 for a purpose which will hereinafter become apparent. At its lower end, 16 the housing 11 is provided with a radially in-turned flange 16 which defines an opening 17. A sleeve 18 concentric with the tubular housing 11 and shank 7 is mounted for axial sliding movements in the opening 17 and is provided at its upper end with an outturned flange 19 which is adapted to engage the inturned flange 16 of the housing 11 upon axial movement of the sleeve 18 outwardly of the housing 11. A coil compression spring 20 has its upper end 21 abutting the annular shoulder 15 of the bushing 13 and its lower end exerting yielding bias on the outturned flange 19 of the sleeve 18.

When the tubular housing 11 is properly located on the shank 7, the sleeve 18 encircles the head 8 of the wrench 6, as shown in Fig. 3. When it is desired to loosen or tighten the jaws 3 of the chuck 1, the head 8 is inserted into the socket 5 of the chuck 1. As illustrated in Fig. 2, insertion of the head 8 into the socket 5 causes the sleeve 18 to move axially inwardly to the interior of the housing 11 against bias of the coil compression spring 20. Manual pressure must be exerted upon the wrench or key 6 to maintain engagement of the head 8 in the socket 5. Upon release of manual pressure upon the wrench 6, bias of the spring 20 will tend to move the sleeve 18 axially outwardly from the housing 11 against the jaw-actuating element 4 and cause the head 8 to be automatically withdrawn from the socket

5. Thus, the operator is prevented from accidentally leaving the wrench in the chuck.

It is important to note that the sleeve 18 is of sufficient internal diameter to enable it to slide freely over the lower end portion of the shank 7. The sleeve 18 forms a protection for the head 8 when the wrench 6 is not being used and prevents the corners thereof from becoming dented or otherwise distorted from impact with other objects, or in the event that the wrench is dropped.

From the foregoing, it will be obvious that I have provided a device which is capable of accomplishing the above objects; and, while I have shown a preferred embodiment of my invention, it will be understood that the same is capable of modification without departure from the spirit and scope of the invention as defined in the claims.

What I claim is:

1. An ejector for a manually-operated chuck wrench of the type having a shank terminating in a chuck-engaging head, said ejector comprising a relatively stationary cylindrical housing adapted to be removably secured to the shank of said wrench and encompass the same above the head thereof, a sleeve concentric with said housing and axially slidable therein from an axially outwardly-projected head-encircling position to a position wherein said sleeve is contained entirely within said casing above said head, stop 20 means limiting movement of said sleeve in an

axially outward direction, and yielding means biasing said sleeve toward its outwardly-projected position.

5. The structure defined in claim 1 in which said stop means comprises a radially outturned flange on said sleeve and a cooperating inturned flange on the bottom end of said housing.

10 3. The structure defined in claim 1 in which said stop means comprises coopearting flanges one on said sleeve and one on said housing at its lower end, said housing being provided with an internal annular shoulder at its opposite end portions, said yielding means comprising a coil compression spring encompassing said shank and having its opposite ends abutting said annular shoulder and the flange on said sleeve.
